UNITED STATES PATENT OFFICE.

EINAR G. C. LOFGREN, OF MINNEAPOLIS, MINNESOTA, ASSIGNOR TO ELECTRO-MECHANICAL DEVELOPMENT COMPANY, A CORPORATION OF MINNESOTA.

PRINTING-TELEGRAPH MACHINE.

Application filed June 18, 1921, Serial No. 478,696. Renewed January 26, 1927.

It is my object to render telegraphic communication more efficient and cheaper by providing comparatively simple means for sending and concurrently recording messages at both the transmitting and receiving ends of a telegraph system.

A further object of my invention is to eliminate or greatly reduce the chance of error in transmitting messages.

10 Another object of my invention is to do away with the necessity of an operator at the receiving end of a telegraph system.

15 A further object of my invention is to provide an instrument of this kind which is adapted to transmit messages over a single main line or circuit.

20 A still further object of my invention is to provide, at each station, a single compact machine which is adapted to transmit, receive and print messages.

Other objects of my invention will appear and be more fully pointed out in the following specification and claims.

25 To attain the above objects I provide an instrument which may be easily adapted for use with any form of telegraphy, whether simplex, duplex, quadruplex, multiplex, selective or wireless as well as with any standard telephone system now in use.

30 To send messages with my improved printing telegraph an operator requires no knowledge of codes and in my present embodiment I have illustrated a machine having a key board arranged like a standard typewriter so that any typist may operate the machine. As the message is transmitted a copy is automatically made and is visible at both the transmitting and receiving ends of the system. The general design of my transmitting and receiving mechanism is like a typewriter, the message being recorded on a sheet of paper, placed in the usual manner, around a stationary roller platen or the record may be made on paper mounted on a separate roll and fed to the platen. The type are mounted in two rows around the periphery of a type wheel which is moved longitudinally with respect to the roller platen and adapted to strike said roller. This longitudinal movement of the type wheel, as well as the movement of the several other parts of the machine, is produced by electro-magnets under the control of local circuits which are completed when the keys are manipulated. Thus, the keys are used only to close local

circuits which operate magnets in connection with the moving parts of the machine and a pair of line relays.

My machine is divided into two distinct sections: first, the selective division, operated by local circuits and including the selective dial, the line relay and line reversing relay under control of the key board, and second, the receiving or printing division controlled by the line circuit and containing 60 a double relay, which is the only instrument directly operated by the line circuit. This relay controls local circuits which actuate printing, shifting, spacing, back-spacing and type carriage return magnets. 70

Selection of characters on the type wheel is accomplished by means of combinations of electrical impulses of different natures. In the present embodiment combinations of impulses flowing in different directions, that is, east to west or positive impulses and west to east or negative impulses are used. However, it is obviously possible to obtain selection of the characters by means of combinations of impulses of different strength or 75 frequency as hereinafter described.

The drawings, forming a part of this specification, illustrate what I at present believe to be the best form of my device but it will be obvious that modifications may be made 85 within the spirit of my invention.

Referring to the accompanying drawings Figure 1 is a plan view of my improved printing telegraph machine; Fig. 2 is a side elevation of the same; Fig. 3 is a section taken on the line 3—3 of Fig. 2 and showing the location of the key board contacts and the several relay instruments and actuating magnets; Fig. 4 is a section taken on the line 4—4 of Figure 1; Fig. 5 is a section taken on the line 5—5 of Fig. 2; Fig. 6 is a section taken on the line 6—6 of Figure 1; Fig. 7 is a detail plan view of the type wheel stop-ratchet; Fig. 8 is a longitudinal fragmentary section through the casing and showing the type wheel carriage and supporting mechanism in front elevation; Fig. 9 is a detail side elevation of the arcuate switch; Fig. 10 is a central vertical section through the type carriage return drum; Fig. 11 is a section 100 taken on the line 11—11 of Fig. 10; Fig. 12 is a detail plan view of the type wheel guide disc; Fig. 13 is a fragmentary transverse section through the roller platen and casing, illustrating diagrammatically the operation 110

of the printing and shifting mechanism; Fig. 14 is a section taken on the line 14—14 of Fig. 13, showing a detail rear view of the printing return spring and adjacent mechanism; Fig. 15 is a fragmentary section through the casing and type wheel supporting mechanism showing the connection between the spacing and printing mechanism; Fig. 16 is a detail plan view of the selective dial switch and actuating magnets; Fig. 17 is an end view of the same partly in section; Fig. 18 is a side elevation of the same partly in section; Fig. 19 is a side elevation of the ribbon carriage; Fig. 20 is a section taken on the line 20—20 of Fig. 19; Fig. 21 is a section taken on the line 21—21 of Fig. 19; Fig. 22 is a section taken on the line 22—22 of Fig. 5; Fig. 23 is a diagram of the wiring of the selective division of my device; Fig. 24 is a diagram of the wiring of the receiving or printing division of my device; Fig. 25 is a chart illustrating a suitable arrangement of combinations of positive and negative impulses used to select the several characters on the type wheel and Fig. 26 is a diagrammatic view showing an alternate form of instruments which adapt my device for use with a quadruplex telegraph system or where the selection of characters is accomplished by varying the strength instead of the direction of electrical impulses sent over the line.

Referring to the accompanying drawings I have used the numeral 1 (Figs. 1 to 6, inc.) 35 to indicate the casing which encloses the several instruments and their wiring and type wheel actuating and supporting mechanism. A roller platen 3, adapted to receive paper for recording a message, is rev- 40 olubly mounted on ears 2 which extend upward from the casing 1 and a type wheel 4 projects from an opening 5 in the top of said casing. The keys 6 and space bar 7 also project from within the casing 1 and are re- 45 siliently supported by springs 8 connected to blocks 9 which are fastened to the casing, (see Fig. 6). Each key is provided with a rigid downwardly projecting conductor 10 which is designed, when the key is depressed, 50 to connect four contacts 11, 12, 13 and 14 mounted on supports 15 which in turn are rigidly secured to the bottom of the casing 1.

Supported at its ends on the casing 1, adjacent to the periphery of the roller 3, is a 55 graduated scale 16 (Figs. 1, 6 and 19) of the kind usually present on typewriters. A 60 slideable ribbon carriage 17 is held in contact with this scale by a small spring 18. The ink ribbon 19 is wound at its ends on suitable drums 20 which feed said ribbon between 65 guide clips 21 on the ribbon carriage, (Figures 1, 2, 6, 19 and 21).

Two rows of type (as illustrated 76 characters) are rigidly mounted on the periphery 70 of the type wheel 4 and said wheel is fast

on the upper end of a spindle 22. This spindle 22 (Figs. 6, 8 and 13) is supported at its lower end on a square rod 23 and is adapted to be tilted so as to bring the periphery of the type wheel 4 against the roller 3 for printing. The spindle 22 is also revoluble at its lower end in a bearing 24 so as to be turned in said bearing for the selection of characters as hereinafter described, (Fig. 8). 75

The bearing 24 is supported by a yoke 25 which is free to tilt on collars 26 at its lower ends. These collars 26 are slideable longitudinally on the rod 23 but are prevented from rotating thereon by the angular cross section of said rod. A pair of arms 27 (Fig. 5) are pivotally connected at their forward ends to the collars 26 and extend rearwardly in parallel relation, being provided with bearings on rods 28 and 29. The rod 28 is rigidly supported at its ends in the casing 1 and the rod 29 extends substantially the length of the machine, being supported at its ends by a pair of arms 30 similar to the arms 27. A fourth rod 31 (Figs. 5, 6, 8 and 13) extends parallel to the rods 23, 28 and 29 and is provided to transmit tilting motion to the spindle 22 on the printing stroke as hereinafter described. 90

Impulse selecting mechanism.

The impulse selecting mechanism, which determines the number and character of impulses sent over the line for each character, includes (Fig. 23) an alternating current 100 generator G, batteries A and B, the key board, a selector dial 32, the line relay 33 and the line reversing relay 34. The circuits comprise an actuating (alternating current) 105 circuit for the selector dial 32 and two selective circuits which determine the number and kind of impulses sent for each character (Figs. 16, 17, 18 and 23). The key board is indicated diagrammatically by a series of parallel wires in connection with 110 the several contact pins on the selector dial casing 35.

The selector dial consists of a stationary outer casing 35 and a series of conductor segments revolvably mounted within the casing 35 and arranged to be rotated by a ratchet wheel 36. A stud 37, rigidly held at its lower end in the casing 1, forms a pivotal support for the conductor segments within the casing 35, the several segments 115 being secured to a sleeve 38 which is revolvble on said stud. The dial proper is divided into upper and lower parts 39 and 40, respectively, the part 40 being of less diameter than the part 39. This part 39 consists 120 of upper and lower intermeshing conductor segments 41 and 42 which are, respectively, divided into halves by insulating material and a bar 43. This bar extends diametrically through the part 39 and is insulated 125

from the segments 41 and 42. The part 40 is also divided into upper and lower conductor segments 44 and 45 which are separated from each other and divided into 5 halves by insulating material. Projecting from the casing 35 is a spring conductor 46, which makes contact with the upper surface of the segment 41 and a similar spring conductor 47 makes contact with the lower surface 10 of the segment 42. Suitable springs on the outer periphery of the casing 35 hold a pair of diametrically opposite pins 48 and 49 in contact with the inter-meshing portions of the segments 41 and 42. Pins indicated by numerals 50 to 65, inclusive, similar to the pins 48 and 49, are also mounted in the casing 35 and are held in contact with the segments 44 and 45 of the part 40 by springs, the pins 51 to 58, inclusive, making 20 contact with the upper segment 44 and the pins 59 to 65, inclusive, making contact with the lower segment 45. The parts 40 and 41 are insulated from each other and from the central sleeve 38 as well as the ratchet wheel 25 36.

When one of the keys is depressed the sleeve 38, carrying the several dial segments, is rotated by the following mechanism; a pair of electromagnets 66, mounted upon the 30 base of the casing 1, by supports 67, is provided with rectangular cores which are joined at one end by a cross bar 68 and formed with inwardly projecting poles 69 at their opposite ends. A permanent magnet 70 is 35 pivotally mounted on the cross bar 68 by means of a pin 71, one end of said magnet being positioned between the poles 69 so as to be actuated thereby as hereinafter described. Rigidly secured to the magnet 70, 40 at its opposite end, is a pair of arms 72 which straddle the ratchet 36 and have inwardly projecting ends formed to engage the teeth of said ratchet for rotating the selector dial. Operation of the selector dial 45 is controlled by a third electromagnet 73. The latter magnet is provided with an armature 74, one end of which is pivotally connected to a spring 75, the opposite end of said armature being bent toward the stud 50 76 and formed with lugs 76 and 77. The spring normally holds the lug 76 against the spring 75 of a switch 78 (mounted on the casing 35) so that said switch is normally closed. A second spring switch 79 is also 55 mounted on the casing 35 but is normally open and adapted to be closed by the lug 77 when the magnet 73 is energized. A small coiled spring 80 holds the armature 74 against a stop 81 when the magnet 73 is de- 60 energized. A cam 82, formed with two radial stops 83, is secured to the sleeve 38 just beneath the ratchet 36 and when the magnet 73 is energized the free end of the armature 74 impinges against and is held 65 in contact with the periphery of said cam.

The line relay 33 and line reversing relay 34 are mounted on the base of the casing 1 by means of supports similar to the supports 67, and blocks of insulating material are rigidly fixed on one end of said supports. 70 These blocks carry the armatures 84 and 85 of the relays 33 and 34, (Fig. 23) said armatures being flexible and secured at one end to said blocks, respectively. The free end of the armature 84 normally makes contact 75 with a terminal 86, but when the coil of the relay 33 is energized makes electrical connection with the armature 85. A strip of conducting material 87 is rigidly mounted in parallel relation with and insulated from the armature 85, being adapted to normally make contact with a terminal 88. The armature 85 makes contact with a terminal 89 until the reversing relay 34 is energized when the armature 85 makes contact with a terminal 90 and the strip 87 simultaneously makes contact with the terminal 89. 85

Operation of impulse selecting mechanism.

When a key is depressed the contacts 11, 12, 13 and 14 (Figs. 6 and 23) beneath the key are connected by the conductor 10. As indicated in the wiring diagram, Fig. 23, each contact 11 is connected with one of the pins 51 to 58; all of the contacts 12 are in circuit with the coil of the electromagnet 73; all of the contacts 13 are in circuit with the battery B and each contact 14 is connected with one of the pins 60 to 65, inclusive. Thus, when a key closes the connection between one series of terminals 11, 12, 13 and 14 current flows from the battery B over the wire 91 to the contact 13, to the conductor 10, to the contact 12, over a wire 92, through the magnet 73 and back to the battery, over the wire 93. This energizes the magnet 73 which closes the spring switch 79. The switch 78, being already closed and said switch and the switch 79 being in circuit with the generator G, the wires 94, 95, 96, 97 and the coils of the magnet 66, an alternating current now flows through said coils so as to vibrate the magnet 70 between the poles 69. Vibration of the magnet 70 is transmitted to the arms 72 and said arms 105 rotate the ratchet 36 together with the cam 82 and selector dial, in the direction indicated by arrows in Figs. 16 and 23, until one of the radial stops 83, of said cam, 110 strikes the end of the armature 74. When this occurs said armature is moved longitudinally against the action of the spring 75 so as to break the generator circuit at the switch 78 and stop rotation of the selector dial. Thus, for each character transmitted the selector dial is rotated one half of one revolution. 115

The above described rotation of the selector dial sends combinations of impulses over the line as follows. Referring to Fig. 120

25 and assuming the letter P is to be transmitted, four negative and three positive impulses will be sent over the line. This combination, as indicated in Fig. 23, will be 5 obtained by a key having its contact 11 connected to the pin 57 on the part 40 of the selector dial and its contact 14 connected with the pin 62 of the part 40. Now when 10 the key for the letter P is depressed, in 15 addition to completing the actuating and control magnet circuits described above the following named circuits are completed. From the battery B current flows over the wire 91, contact 13, conductor 10 (and divides) a part of the current flowing over 20 the wire 98 to the pin 57 and a part flowing by the wire 99 to the pin 62. As the selector dial rotates current flows from the pin 57 to one half of the segment 44 and as soon as 25 the division point of said segment has passed the pin 59, current flows from said segment over the pin 59 and a wire 100, through the coil 33 and returns to the battery B via a wire 101 and the wire 93. This energizes 30 the line relay to connect the free end of the armature 84 with the fixed end of the armature 85. Current now flows over the line from the battery A via a wire 103, to the terminal 89, by the armatures 85 and 84, 35 over wires 104 and 105, to the spring contact 46 and from said contact to the upper intermeshing segment 41, then to the pin 49, and each time one of the intermeshing portions of said segment passes the pin 49, 40 an electrical impulse will be sent over the line via the ground connection 106. The circuit is completed through the ground connection of the receiving instrument, the current returning over the line wire 102, wires 107, 108, the terminal 88 and wire 109. When the pin 57 is connected to the 45 actuated key in the line relay circuit, said circuit will be closed until the half of the segment 44 in contact with the pin 59 has passed the pin 57 during which time seven 50 of the intermeshing portions of the segment 41 will have passed the pin 49. Thus, the total number of impulses sent for each character is determined by the connection with the pins 51 to 58. The number of positive impulses sent depends upon which of the pins 60 to 65, inclusive, is in connection with the contact 14 of the particular key. In the case of the letter P in which the pin 62 is 55 connected to the contact 14 the following circuits are completed. Current which flows from the battery B to the pin 62, as described above, passes by one of the halves of the segment 45 to the pin 50 (as soon as the dial rotates) and from said dial over a wire 110 to the coil of the reversing relay 34 and returns to the battery B via a wire 111 and the wire 93. This energizes the reversing relay 60 and connects the terminal 90 with the armature 85 and the terminal 89 with the strip 65

87. The terminals of the battery are thus reversed and current flows over the line in the reverse direction as follows: from the battery A current flows to the terminal 90, over the wire 109, thence via the armatures 85 and 84, the wires 104, 105, the contact 46, intermeshing segment 41, pin 49, ground 106 over the line returning via wires 102, 107, terminal 86, wire 108, strip 87, terminal 89 and wire 103 to the battery. The spring 47 (Fig. 18), which makes contact with the lower intermeshing segment 42, is connected by wires 112 and 113 to the line wire 102 past the battery. Thus, as the dial rotates positive impulses are sent over the line until the division point of the segment 45 has passed the pin 62 or until three positive impulses have been sent over the line. As soon as the pin 62 has been passed, the circuit, through the coil of the reversing relay 34, is broken and the armature 85 returns to its normal position shown in Fig. 23. When negative impulses are sent, until the segment 44 has passed the pin 57, in the present instance, four of these negative impulses will be sent. Thus, for the letter P three positive and four negative impulses are sent over the line 102.

As stated above the characters are arranged on the type wheel 4 in two rows, one above the other. It is, therefore, necessary to differentiate the combination of impulses sent over the line for the selection of the lower from the upper row of type. This is done by lengthening the first impulse sent over the line for the selection of the characters on the lower row of type. The bar of conducting material 43, which extends diametrically through the upper part 39 of the selector dial, is insulated from the segments 41 and 42 and the sleeve 38 and its ends extend to the periphery of the part 39 so as to make contact with the inner ends of the pins 48 and 49 when the dial rotates.

Whenever the dial begins to rotate, the pin 48 and the bar 43 thus make electrical connection between the pins 48 and 49 and complete a circuit from the line 102 through the wires 113 and 116, a switch 115, a wire 114 to the pin 48, through the bar 43, pin 49, to the ground 106. This completes the line circuit to permit messages to be sent simultaneously in both directions as in the duplex telegram system. The switch 115 is actuated by one of the keys 6 (the shift key) and when said key is depressed the circuit, between the wires 116 and 114, is broken and the following circuit is completed. As the dial switch 32 commences to rotate current will flow from the battery A (the line relay 34 being actuated simultaneously as described above) over the wire 109, terminal 88, armature 87, wire 108, terminal 86, wire 107, over the line 102, returning from the ground 106 and flowing by the pin 49, bar 43, 125

pin 48, wire 114, switch 115, wire 117, wire 104, armature 84, armature 85, terminal 89 and wire 108 back to the battery. This sends an impulse over the line through the bar 43 which lengthens the first impulse (the impulse sent through the pin 51 or 60) when the shift key is actuated.

Referring to the chart (Fig. 25) the small numerals in the upper right hand corner of each square indicate the position of the characters on the type wheel and the larger letters and figures in the center of each square indicate the character. The squares to the right and beneath the heavy line 118 represent the blank spaces on the type wheel. As will be readily understood from this chart, the maximum number of impulses used to transmit any character is eight. Thus, the letter C is selected by using seven negative impulses and one positive, other characters being selected by various other combinations not exceeding eight. A single negative impulse is employed to operate the spacing and type wheel returning magnets and two negative impulses are employed to operate the back spacing magnet as herein-after described.

The main line or circuit includes not only the battery A, the armatures of the line relay and reversing relay and the part 39 of the dial switch, but also two coils 119 and 120 in series at both the sending and receiving ends of the line, (Fig. 24). One side of the circuit, through the coils 119 and 120, is grounded at 121.

Receiving or printing division.

The printing division is controlled by a pair of relays consisting of the coils 119 and 120 (Figs. 6 and 24), the armatures 125 and 126 and permanent magnets 122 and 123, the coils 119 and 120 being in series in the line circuit 102 (Figs. 23 and 24). The coils 119 and 120, through which the line current passes, are supported upon the base of the casing 1 (Figs. 3, 6, and 24) near the right hand end thereof and permanent horse-shoe magnets 122 and 123 surround said coils, the poles of said magnets being positioned at opposite sides of the open upper ends of hollow cores within said coils. Insulation 124, between the casing 1 and the bottom of the coils 119 and 120, supports the lower ends of armatures 125 and 126, said armatures being pivotally mounted in said insulation in substantially upright position within the hollow cores of said coils. The upper ends of the armatures 125 and 126 are held outward by springs 127 and an insulated plate 128, provided with a binding post 129 and contact screws 130 and 131, is mounted on the upper surface of the adjacent poles of the magnets 122 and 123. By this arrangement current flowing through the coils 119 and 120 will polarize the armatures 125

and 126 with the upper ends of said armatures of opposite polarity so that the armature 125 is brought against the contact screw 130 by current flowing in one direction through the coils 119 and 120 and current flowing in the opposite direction will cause the armature 126 to be brought against the screw 131.

Dogs 132 and 133 are pivotally mounted on the upper ends of the armatures 125 and 126, respectively, (Figs. 4 and 6). These dogs are adapted to engage rack quadrants on the lower ends of levers 134 and 135, said levers being supported by a bracket 136, which is secured to the end of the casing 1, (Figs. 3, 4, 5, 6 and 8). The lever 135 has its fulcrum point at 137 on the bracket 136 and its upper end is connected by a link 138 to the upper end of the lever 134. A second link 139 connects the lever 134 with the upper end of a crank 140, said crank being secured to the end of the square rod 23. The pin 134^a, which connects the link 139 with the lever 134, projects and is slidably held in a slot (indicated at 134^b in Fig. 6) in the bracket 136. A pair of detents 141 are pivotally mounted, adjacent to the racks on the lower ends of the levers 134 and 135, upon a cross bar 142, said bar being also tiltably connected to the bracket 136 by a pin 143. The cross bar 142 is held upward, so as to cause the pointed upper ends of the detents 141 to engage the teeth of the adjacent racks; by a light spring 144 and a series of small pins, mounted, respectively, on the bar 142 above the several dogs 132 and 133 and the detents 141 form stops for upward movement of said dogs and detents. A series of small springs, coiled around the pivot pins of said dogs and detents, hold the same upward against said pins. By this arrangement the dogs 132 and 133 and the detents 141 are normally held in engagement with the racks on the lower ends of the levers 134 and 135 but downward tilting movement of the cross bar 142 will disengage said dogs and detents from said racks.

A second crank 145 (Figs. 6 and 8) is secure against rotation on the rod 23 but free to slide longitudinally thereon with the type wheel carriage. The crank 145 is arranged to engage a pin 146 on a stop bar 147 and the latter bar is tiltably mounted on the rod 23 adjacent to the crank 145, being provided to engage the teeth of a helical ratchet 148. This ratchet is fast on the type wheel spindle 22, above a pinion 149, which is also fast on said spindle. A rack quadrant 150 is mounted adjacent to said pinion upon the upper end of a support 151, which is tiltable on one of the collars 26. The support 151 extends beneath the rod 23 and a spring 152, connected to the lower extremity of said support and to the adjacent arm 27, tends to hold the upper end of the support 130

151 downward and to the left (Fig. 6). To return the crank 145 to starting position, after each printing stroke, I provide a spring 145^b which connects a projection 145^a on said crank with one of the arms 27 (see Figs. 6 and 8). A type wheel guide disc 153 (Figs. 6 and 12) is fast on the spindle 22, just beneath the type wheel 4 and is arranged to engage a tooth 154 in notches 155 in the periphery of said wheel, at the end of each printing stroke.

The printing mechanism proper is operated by a magnet 156 (Figs. 3, 5 and 13) which, like the shifting magnet 157, spacing magnet 158, back spacing magnet 159 and type wheel return magnet 160, consists of a solenoid coil having a suitably designed plunger. The rod 31 transmits tilting motion to the spindle 22, by means of the yoke 25, and is supported at one end by an arm 161 and at its other end by a crank 162. The arm 161 and crank 162 are tiltably supported on bushings near the extremities of the square rod 23, while the end 162^a of the crank 162 is pivotally connected by a link 163 to the upper end of the plunger of the magnet 156. Dependent from the arm 30 is a spring abutment 164 (Figs. 13 and 14). This abutment is rigidly secured to the lower edge of the arm and its inwardly projecting end 164^a is slotted to receive the plunger link 163. A tension spring 165 is coiled around the link 163, beneath the abutment 164 and is secured at its upper end to said abutment and at its lower end to the plunger of the magnet 156. This spring tends to withdraw the plunger from the magnet 156 and to return the type wheel 4 after the printing stroke.

40 A link 166, similar to the link 163, connects the rod 29, adjacent to the arm 30, with the plunger of the shifting magnet 157. Thus, as will be readily understood, when the magnet 157 is energized its plunger will be drawn downward together with the link 166 and rod 29. This tilts the supporting arms 30 on the rod 28 and raises the square rod 23, carrying the type wheel 4, so as to strike the platen 3 with the lower row of type on the printing stroke.

Three racks 167, 168 and 169 (Figs. 4, 5 and 22) are provided to stop and release the type wheel carriage under the action of the spacing magnet 158, back spacing magnet 159 and type wheel release magnet 160. These racks are provided with teeth on their upper edges which engage co-acting teeth on a block 170, mounted between the arms 27 on the rod 28. Pins 171 pivotally connect the rack 168 with supporting and actuating bars 172 and 173 and said pins also support the rack 167 in horizontal slots 174 in the latter rack. Thus, the rack 167 is supported by, but free to move longitudinally on the pins 171 and the rack 168 is supported by

said pins. The bar 172 is pivotally connected at its end 172^a to the casing 1 and is joined at its opposite end to the bar 173 and to the forward end of an actuating lever 176 by a pin 175. The pin 175, which connects the bar 172 to the lever 176, passes through a horizontal slot in the end of the bar 173, the opposite end of said bar being pivotally connected by an ear, between the levers 134 and 135, to the bracket 136. The rearward end of the lever 176 is pivotally connected to the casing 1 and said lever is arranged to be actuated by the magnet 160, the core of said magnet being connected by a link 177 to said lever intermediate its ends. A spring 178 (Fig. 22) connected to the casing 1, tends to withdraw the plunger from the magnet 160 and to raise the forward end of the lever 176. Thus, when the magnet 160 is energized the racks 167 and 168 are moved downward out of engagement with the block 170 (the rack 167 being free to move longitudinally, independently of the rack 168) and when current ceases to flow in the magnet 160 the spring 178 returns said racks to engagement with the block 170.

A lug 167^a rigidly secured to the lower edge of the rack 167, is formed with a bevelled surface, which is designed to engage a bevelled surface on a lug 142^a on the cross bar 142. These co-acting lugs operate to depress the spring supported end of the cross bar 142 whenever the rack 167 is moved downward for back spacing or for releasing the type wheel carriage and also when said rack is moved longitudinally toward said cross bar in the spacing operation.

In connection with the above described type wheel release mechanism I provide means for rotating the roller platen 3 a part of a revolution each time the magnet 160 is energized. This mechanism consists (Figs. 4, 5 and 22) of a substantially vertical link 257 connected to the lever 176 at its lower extremity and joined to a substantially horizontal lever 258 at its upper end. The latter lever is pivotally mounted on the casing 1 by means of a pin 259 and is arranged to actuate a finger 260 to engage a ratchet 261, which is fast on the supporting spindle 115 of the roller platen 3, so that each time the magnet 160 is actuated the link 257 is drawn downward to raise the finger 260 and turn the ratchet 261 to allow space between lines of the printed characters on said roller.

The rack 169 is supported by two bars 179 and 180 (Figs. 5 and 22) which are pivotally connected to each other at their adjacent ends and at their remote ends to said rack. Brackets 181, extending upward from the base of the casing 1, form pivotal supports for the bars 179 and 180 and a link 182 connects the middle of the bar 179 with the plunger of the magnet 159. The rack 169 is normally out of engagement with

the block 170 and its longitudinal position, in relation to the rack 168, is such that its teeth are positioned intermediate the teeth of the latter rack. By this arrangement the 5 rack 169 is moved upward into engagement with the teeth on the block 170 when the magnet 159 is energized. A dependent fork 183, rigidly secured at its upper end to the bar 179 (Figs. 5 and 22) and straddling the 10 upper edge of the lever 176, at its lower end transmits downward movement of said bar to said lever. The fork 183, thus causes the lever 176 and bars 172 and 173 to depress the racks 167 and 168 when the magnet 159 is energized.

The spacing magnet 158 is connected with the rack 167 by linkage consisting of a lever 184 and a crank 185 (Figs. 4 and 5). The crank 185 is pivotally supported on a bracket 20 186 and connected to the rack 167 by a pin through a vertical slot in the upper end of said crank. The rearward end of the lever 184 is connected by a suitable link to the plunger of the magnet 158 and the forward 25 extremity of said lever is connected by a substantially vertical link 187 to another lever 188 which has its fulcrum point in a pair of ears 188^a on the casing 1. Dependent from the printing magnet crank 162 is 30 a link 189 which is pivotally connected to the lever 188. This link transmits downward motion from the crank 162 to the lever 188 when the printing magnet 156 is energized whenever the printing stroke occurs.

A drum 190, upon which a cord 191 is wound, is provided to move the arms 27, carrying the type wheel and connecting the mechanism, longitudinally on the rods 23, 28, 29 and 31 against a padded stop 192 when the racks 167 and 168 are released 40 from engagement with the block 170 (Figs. 2, 4, 5, 8, 10 and 11). The cord 191 is secured at one end to the periphery of the drum 190, passes through an aperture 193 in the casing 1, around a small pulley 194, through a perforation 191^a (Fig. 9) in the adjacent arm 30 and is secured at its opposite end to the adjacent arm 27. The drum 190 is revoluble upon a stud 195 which projects outward from the end of the casing 1 and a helical spring 196, within said drum, is secured at its inner end to the stud 195 and at its outer end to the inner surface of a disc 190^a, which is revoluble on the stud 195 independently of the drum proper. A pawl 197, mounted on the inside surface of the disc 190^a is arranged to engage an internal ratchet gear 198 formed on the drum proper. The pawl 197 and ratchet 198 are arranged 50 so that rotation of the disc 190^a will change the tension of the spring 196. The pawl 197 may be released from engagement with the rack 198 to lessen the tension of the spring 196 by inserting a suitable pin

through a perforation 199 in said drum. 65 The perforation 191^a, in the arm 30, adjacent to the drum 190, is provided to guide the cord 191 past the arcuate switch mechanism.

Means, for raising the ribbon 19 into the 70 path of the type on the printing stroke, consist of substantially upright rods 200 slideable at their upper ends in a guide 201 and pivotally connected at their lower ends to a pair of levers 202. These levers are tiltably supported on ears 203 formed on the arms 27, and joined at their ends adjacent to the rod 23 to a crank 204. The connection between the levers 202 and the crank 204 consists of a rod 205 fastened at its ends to 75 said levers and slideable in a slot in the end of said crank. The crank 204 is connected by a pin 206 to the yoke 25, said pin being held at its ends in said yoke and secured to 80 said crank in an ear 207. The support 201 straddles the arms 27 and has bearings at its lower end on the rod 28. When the yoke 25 tilts on the printing stroke the crank 204 is carried downward to its dotted line position 85 (Fig. 19), the ribbon carriage 17, being carried upward to its dotted line position.

The arcuate switch, shown in detail in Fig. 9, is used to close severally the circuits controlling the magnets 156 to 160, inclusive. This switch is mounted upon the outer surface of one of the arms 30 (Figs. 5, 8 and 9) and consists of large and small gear segments 208 and 209, a wiper bar 210 and an arcuate support 211 having three insulated 90 contact buttons 212, 213 and 214 mounted thereon. The segmental gear 208 is fast on the square rod 23 and formed with a circular periphery 215 and gear teeth 216. These teeth engage teeth on the gear segment 209, and a lug 217, formed on the latter gear segment, is arranged to strike the circular portion 215 and stop rotation of the segment 209 when the teeth 216 become disengaged from the teeth on the segment 209. A spindle 218 is revolvably mounted in the 100 arm 27 and supports the segment 209 and the wiper 210, said segment and wiper being fast on the end of said spindle. By this arrangement when the rod 23 is turned in the direction indicated by an arrow in Fig. 9 the wiper 210, which is made of conducting material, makes electrical contact successively with each of the buttons 212, 213 and 214.

A short impulse relay 219 and a long impulse relay 220 (Fig. 24) are used to control the several actuating magnets, the relay 219 is used to control the printing magnet 156, the spacing magnet 158 and the relay 220 is used to 110 control the shifting magnet 157 and type wheel carriage release magnet 160. The relays 219 and 220 are similar in construc- 115 120 125

tion but the armature 221 of the relay 219 is lighter than the armature 222 of the relay 220. Insulated ears 223 support the armatures 221 and 222 on the upper ends of the 5 relay coils, said armatures being tiltably connected to said ears. The over-hanging ends of the armatures 221 and 222 are arranged to normally make contact with screws 224 and 225, respectively mounted in supports 226 10 and 227. Insulated contact screws 228 and 229 are severally mounted on the upper ends of the supports 226 and 227, being arranged to make electrical contact with the armatures 221 and 222 when said armatures are attracted to the cores of the relay coils.

Electrical operation of printing division.

A local battery C (Fig. 24) furnishes current for the printing division of my device and one terminal of this battery is connected by branching wires 230 and 231 with the armatures 125 and 126, respectively of the character selecting relays. When the coils 119 and 120 are energized, by an impulse from the line 102, the armature 125 or 126 is brought momentarily in contact with the terminal 130 or 131 and completes the following circuit through the relays 219 and 220. An impulse is sent from the battery C 20 through the terminal 130 or 131 to the binding post 129 over a wire 232; thence branches to the supports 126 and 127 and passes through the contact screws 224 and 225, to the armatures 221 and 222; then over wires 30 233 and 234, through the coils of both relays, and returns to the battery over wires 235 and 236. If a short impulse has been sent through the coils 219 and 220 the impulse over the wire 232 will be short and only the 35 armature 221 will have time to act but if a longer impulse has been sent through said coils both the armature 221 and 222 will be actuated and severally close the circuits between said armatures and the terminal screws 228 and 229, respectively. Now in 40 case a single short impulse is sent over the line the arcuate switch is turned as herein-after described to bring the wiper 210 in contact with the first button 212 and the circuit between the screw 228 and armature 221 is 45 closed. Current flows from the battery C over a wire 237, the wiper 210, a wire 238, through the spacing coil 158, over a wire 239, terminal 228, armature 221, wire 233, the coil of the relay 219 and returns to the 50 battery over the wire 235. Thus, the spacing magnet is actuated when a single short impulse is sent over the line. In case a single long impulse is sent over the line the local circuits will be closed through the arcuate switch to the contact button 212 and also between the armatures 221 and 222 and the terminals 228 and 229, respectively. Current now flows from the battery over the 55 wire 240, through the coil 160, over the wire 241, terminal 229, armature 222, wire 234, through the coil of the relay 220, and returns to the battery over the wires 236 and 235. Thus, the type carriage release magnet 160 is actuated when a single long impulse is 60 sent over the line. In order to allow time for the type carriage to travel the length of the supporting rods, a shunt circuit 242, 243, 244 is provided and arranged to be closed by a bar 245 when the magnet 160 is 65 energized. A lug 246, on the plunger link 177, engages the switch bar 245 to close the circuit when the plunger is drawn into the coil. This shunt circuit is broken by a 70 spring switch 247 (Figs. 5 and 24) which is 75 opened by a finger 248 on one of the arms 27 when the carriage is brought against the 80 step 192.

When two short impulses are sent over the line the wiper 210 of the arcuate switch is 85 moved to the second contact button 213 to complete the following circuit. Current flows from the battery C over the wire 237, wiper 210, a wire 249, through the coil of the back spacing magnet 159, over the wires 250, 251, 252, terminal 228, armature 221, wire 233, the coil of the relay 219 and returns to the battery over the wire 235. When more than two impulses are sent over 90 the line (for the selection of characters on the type wheel) the arcuate switch wiper 210 is moved to the contact 214. When the impulses are of short duration current flows from the battery C over the wire 237, wiper 210, a wire 253, a wire 254, to the coil of the 95 printing magnet 156 by the wires 251, 252, the terminal 228, armature 221, wire 233, the core of the relay 219 and wire 235 to the battery. If a long impulse is sent over the line in combination with a plurality of short 100 impulses the shifting magnet 157 will be actuated as well as the printing magnet 156. In this case the current divides from the wire 253, a part flowing over the wire 254, through the printing magnet, as described 105 above, and a part flowing over a wire 255, through the shifting magnet 157, over wires 256 and 241, the terminal 229, armature 222, wire 234, the coil of the relay 220 and returns to the battery over the wire 235 and 110 236.

The arrangement of the permanent magnets 122 and 123 is such that their adjacent poles are alike and the winding of the coils 119 and 120 is such that when 115 current flows through said coils the armatures 125 and 126 will be magnetized with their upper ends of opposite polarity. Thus, current flowing through said coils in one direction will cause the armature 126 to be 120 brought against the contact screw 131 and current in the opposite direction will cause 125 the armature 125 to be brought against the

screw 130. In the illustrated embodiment of my invention positive impulses sent over the line actuate the armature 126 and negative impulses actuate the armature 125.

5 Mechanical operation of printing division.

The design of the levers 134 and 135 (Figs. 6 and 8) and the linkage connecting said levers with the stop bar 147 is such that 10 movement of the armature 126 to contact with the screw 131 will tilt the lever 135 on the pin 137 sufficiently to stop rotation of the type wheel 4 as soon as said wheel has turned a distance equivalent to eight characters 15 on the printing stroke and movement of the armature 125 to contact with the screw 130 will tilt the lever 134 on the pin 134^a to allow rotation of the type wheel 4 a distance equal to one character on said 20 wheel. To illustrate, when the letter P is to be printed (the selection being accomplished by three positive and four negative impulses sent over the line wire 102) each of the three positive impulses will actuate the 25 armature 126 to move the stop bar 147 into position to engage the ratchet 148 in the twenty-fourth notch and each of the four succeeding negative impulses will actuate the armature 125 to move the stop bar 147 30 so as to engage the ratchet 148 after said ratchet has turned an additional four notches. This stops the type wheel rotation at a point where the twenty-eighth character or the letter P on the type wheel is adjacent 35 to the roller platen 3. Simultaneous with this movement of the stop bar 147 the articulate switch (Fig. 9) is actuated. The rod 23 being turned in the direction of the arrow, as described above, the wiper bar 210 40 will be moved successively into contact with the buttons 212, 213 and 214, through the gear segments 208 and 209 and the spindle 218 to successively complete the spacing, back spacing and printing circuits. However, 45 the movement of the wiper 210 over the buttons 212 and 213 in the case of the selection of the letter P is so rapid that the spacing and back spacing magnets will not have time to operate but when the third 50 negative impulse turns the rod 23 to bring the wiper 210 into contact with the button 214, the lug 217 will strike the circumference 215 of the gear segment 208 to stop the wiper 210 on the contact 214. Further rotation of 55 the rod 23 caused by a greater number of impulses is permitted by the sliding action of the circumference 215 on the lug 217. Thus, 60 the printing magnet circuit is completed when three or more negative impulses or one or more positive impulses are sent over the line.

As the rod 31 is moved forward on the printing stroke the spindle 22 is rotated by the pinion 149 (Figs. 6 and 8) until the

ratchet 148 strikes the stop 147, when rotation of the spindle 22 is stopped with the selected character adjacent to the roller platen.

3. Further movement of the type wheel on the printing stroke tilts the rack 150, the support 151 and stop bar 147 against the action of the spring 152. This spring and the spring 145^b return the several parts to starting position when the printing magnet plunger is released, and the cross bar 142 is moved downward to disengage the dogs 132 and 133 and detents 141 from the racks on the lower end of the levers 134 and 135 by means of co-acting lugs 167^a and 142^a, respectively.

Shifting from the upper to the lower row 80 of type, on the wheel 4, is accomplished simultaneously with the above printing action when the magnet 157 is energized, by an impulse of longer duration, as described above. When it is desired to space between words 85 in a message, the space key is depressed so as to send a single short impulse over the line as described above. This single short impulse operates to turn the rod 23 and brings the wiper 210 in contact with the button 212, the effect being to energize the magnet 158 and depress the adjacent end of the lever 184 while the opposite end of said lever is held stationary by its connection with the crank 162. The crank 185 moves 90 the rack 167 together with the type wheel carriage longitudinally as described above. When a single long impulse is sent, the magnet 160 is energized; the free end of the lever 176 is depressed and by means of the bars 172 and 173 and the pins 171, the racks 167 and 168, are simultaneously moved 95 downward. This releases the teeth on said racks from the block 170 and allows the spring actuated drum 190 to draw the type wheel carriage to the left (Figs. 4, 5 and 8) 100 against the cushion stop 192. As the arm 27 strikes the stop 192 the finger 248, on said arm, strikes and opens the spring switch 247 to break the circuit through the magnet 160. 105 Actuating the magnet 160 also operates to turn the roller 3 by means of the link 257, lever 258 and finger 260.

The back spacing key operates to send two impulses over the line and causes the wiper 210 to be moved to the button 213, thus, 115 closing the circuit through the magnet 159. Operating the magnet 159 tilts the bar 179 on the bracket 181 and through the bar 180 raises the rack 169 to engagement with the teeth on the block 170 and simultaneously (by means of the fork 183) depresses the lever 176 to disengage the racks 167 and 168. The teeth on the rack 169 being intermediate 120 the teeth on the racks 167 and 168, the type wheel carriage will now move backward half 125 a space, and, when the magnet 159 is de-energized, will allow the racks 167 and 168

to move upward and said carriage will move back another half space.

*Alternate form of instruments and wiring
for quadruplex telegraphy.*

Instruments and wiring to adapt my device for use with quadruplex telegraphy are illustrated in Fig. 26. In this alternate form combinations of impulses varying in strength are employed to select the several characters. Two relays 33^a and 34^a are substituted for the line relay 33 and line reversing relay 34, respectively, of the selecting division, and printing division control relays 119^a and 120^a are substituted for the relays with coils 119 and 120 of the preferred form. The connections of the coils of the relays 33^a and 34^a are identical with those of my preferred form and the line wire 102 is connected in the same manner with a wire 104 leading to the armature 262 of the relay 33^a. The latter armature is adapted to vibrate between a terminal 263 and a fixed end of the armature 264 of the relay 34^a, the free end of the latter armature being adapted to vibrate between two terminals 265 and 266, respectively. The zinc terminal of a battery 'A' is connected by a wire 267, to the terminal 263, and said battery is divided, one carbon terminal being connected by a wire 268 to the terminal 265 and the other by a wire 269 to the terminal 266. By this arrangement when the dial 32 operates to send impulses through the relay 33^a only, weak impulses will be sent over the line from the middle of the battery A' by the wire 268, terminal 265, armatures 264 and 262 and the wire 104. When the relay 34^a is also energized by impulses from the circuits containing the pins 60 to 65 inclusive, stronger impulses will be sent over the line from the battery A' through the wire 269, terminal 266, armature 264, armature 262 and wire 104.

The above combinations of impulses of varying strength are sent through the coils of the relays 119^a and 120^a. These relays are designed so that the stronger impulses sent over the line will actuate both of the armatures 125^a and 126^a of said instruments but weaker impulses will affect only the armature 125^a of the relay 119^a. Thus, strong impulses correspond to positive impulses in the preferred form and weaker impulses to negative impulses in the preferred form of my device.

It will be readily understood that when impulses of "two natures" or "different natures" are mentioned in the following claims that impulses of two or different strengths or frequency are included as well as those in different direction or east to west and west to east.

Having described my invention what I

claim as new and desire to protect by Letters Patent is:

1. In a machine of the class described, the combination of a main line circuit, means for sending impulses of different natures over said circuit, armatures at the receiving end of said circuit adapted to be actuated when impulses of different natures are received, each of said armatures being affected by impulses of one nature only, a series of type characters divided into groups, means actuated by one of said armatures for selecting pre-determined groups of said characters, and means actuated by another of said armatures for selecting pre-determined characters in each group. 70

2. In a machine of the class described, the combination of a main line circuit, means for sending impulses of different natures over said circuit, a single pair of armatures at the receiving end of said circuit adapted to be actuated when impulses of different natures are received, a series of type characters divided into groups, means actuated by one of said armatures for selecting pre-determined groups of said characters, and means actuated by the other of said armatures for selecting pre-determined characters in each group. 85

3. In a machine of the class described, the combination of a main line circuit, means for sending positive and negative impulses over said circuit, an armature adapted to be actuated only when positive impulses are sent over said circuit, a second armature adapted to be actuated only when negative impulses are received, a series of type characters divided into groups, means actuated by one of said armatures for selecting pre-determined groups of said characters, and means actuated by the other of said armatures for selecting predetermined characters in each group. 95

4. In a machine of the class described the combination of a main line circuit, means for sending impulses of different natures over said circuit, armatures at the receiving end of said circuit adapted to be actuated when impulses of different natures are received, each of said armatures being affected by impulses differing from those affecting another of said armatures, ratchets arranged to be severally moved by said armatures, a series of type characters divided into groups, means actuated by one of said ratchets for selecting predetermined groups of said characters and means actuated by another of said ratchets for selecting predetermined characters in each group. 110

5. In a machine of the class described the combination of a main line circuit, means for sending impulses of different natures over said circuit, armatures at the receiving end of said circuit adapted to be actuated by 115

impulses of different natures, the operating magnets for said armatures being arranged in series in a circuit, ratchets arranged to be severally moved by said armatures, a type wheel carrying a series of type characters divided into groups, means actuated by one of said ratchets for selecting predetermined groups of said characters and means actuated by another of said ratchets for selecting predetermined characters in each group.

6. In a machine of the class described, the combination of a main line circuit, means for sending impulses of different natures over said circuit, armatures at the receiving end of said circuit adapted to be actuated by impulses of different natures, a type wheel carrying a series of characters divided into groups, means actuated by one of said armatures for allowing the turning of said wheel through relatively large angles to thereby select predetermined groups of said characters and means actuated by another of said armatures for allowing said wheel to turn through relatively small angles to select thereby pre-determined characters in each group.

7. In a machine of the class described, the combination of a main line circuit, means for sending impulses of different natures over said circuit, armatures at the receiving end of said circuit adapted to be actuated by impulses of different natures, a type wheel carrying a series of characters divided into groups, a ratchet actuated by one of said armatures, means operatively connecting said ratchet and wheel for turning said wheel through relatively large angles to thereby select pre-determined groups of said characters and a ratchet and means actuated by another of said armatures for turning said wheel through relatively small angles to select thereby pre-determined characters in each group.

8. In printing telegraph mechanism, a series of type characters, a single pair of armatures adapted to be actuated by impulses of different natures, mechanical means connecting said armatures with said type whereby the selection of pre-determined type characters is effected by vibrations of said armatures, and means for producing combinations of impulses to actuate said armatures.

9. In a device of the class described, a main line circuit, a relay instrument having its coils in said circuit, local relays of different sensitiveness under control of said first mentioned instrument and magnets adapted to actuate printing spacing and back spacing mechanism, severally arranged in local circuits under control of said local relays.

10. In a device of the class described, the combination of a main line circuit, means for sending impulses of different natures over said circuit, a relay instrument in the receiv-

ing end of said circuit, having two armatures adapted to be actuated by impulses of different natures, a series of type characters divided into groups, a lever adapted to be actuated by one of said armatures for selecting predetermined groups of said characters, and a lever adapted to be actuated by the other armature for selecting predetermined characters in each group.

11. In a machine of the class described, a type wheel, means for rotating said wheel for the selection of type thereon and means for stopping rotation of said wheel in predetermined angular positions comprising, a stop bar, levers linked together and arranged to severally move said stop bar through different arcs and magnetic means for actuating said levers.

12. In a machine of the class described, a type wheel, means for rotating said wheel for the selection of type thereon and means for stopping rotation of said wheel in predetermined angular positions comprising, a stop bar, levers linked together and arranged to severally move said stop bar through different arcs, ratchets on said levers and magnetic means having armatures arranged to engage said ratchets.

13. In a machine of the class described, a type wheel, means for rotating said wheel for the selection of type thereon, and means for stopping rotation of said wheel in predetermined angular positions comprising, a stop bar, levers linked together near one end and arranged to severally move said stop bar through different arcs, means for normally holding the opposite end of said levers stationary and magnetic means for actuating the normally stationary ends of said levers.

14. In a device of the class described, a line circuit, a plurality of keys in local circuits, a rotary dial switch under control of said keys for sending series of impulses over said line circuit, a series of contact elements arranged on said switch to determine the total number of impulses sent over said line circuit, another series of contact elements on said switch adapted to determine the number of impulses of a certain nature that are sent over said line circuit, a plurality of relays having armatures in said line circuit to control the same, one of said armatures being arranged to transmit all impulses to said line circuit and another of said armatures being arranged to control the nature of impulses sent over said line circuit.

15. In a device of the class described, a line circuit, a plurality of keys in local circuits, a rotary dial switch under control of said keys for sending series of impulses over said line circuit, and a plurality of relays having armatures in said line circuit to control the same, one of said armatures being arranged to transmit all impulses to said

line circuit and another of said armatures being arranged to control the nature of impulses sent over said line circuit.

16. In a device of the class described, a plurality of keys in local circuits, means under control of said keys for sending series of impulses over said line circuit and a plurality of relays having armatures in said line circuit to control the same, one of said armatures being arranged to transmit all impulses to said line circuit and another of said armatures being arranged to control the nature of impulses sent over said line circuit.

17. In a device of the class described, a line circuit, means for sending series of impulses over said line circuit, and a plurality of relays having armatures in said line circuit to control the same, one of said armatures being arranged to transmit all impulses to said line circuit and another of said armatures being arranged to control the nature of impulses sent over said line circuit.

18. In a printing telegraph system, a main line circuit, a plurality of manually operated typewriters provided with keys in local circuits, electrical printing mechanism arranged within each of said typewriters to be controlled by combinations of impulses of different natures passing over said main line circuit and means under control of said local circuits for sending combinations of impulses of different natures over said main line circuit, said means comprising a two part selector dial, adapted to be rotated when a key is manipulated, and a plurality of line relays, one part of said dial being arranged to control the line circuit through the armatures of said relays and the other part of said dial being arranged to control the operation of said relays.

19. A printing telegraph system comprising a two part selector dial, one part of said dial having upper and lower semi-circular conductor segments mounted therein and a plurality of elements arranged to make contact with said segments, the other part of said dial having upper and lower intermeshing conductor segments and elements adapted to alternately make contact with said segments, a plurality of manually operated typewriters provided with keys in circuit with said dial, means under control of said keys severally for rotating said dial a predetermined degree, line relays in circuit with said dial, a single line circuit controlled by said relays and character selecting relays in said line circuit at both the sending and receiving stations.

20. In a device of the class described, a line circuit, a plurality of keys in local circuits, a rotary dial switch under control of said keys for sending series of impulses over said line circuit, a relay having an armature in said line circuit arranged to transmit all impulses to said line circuit, a second relay

having an armature arranged to control the nature of impulses sent over said line circuit, a series of contact elements, on said switch, in circuit with the coil of said first mentioned relay, to determine the total number of impulses sent over said line circuit, and a second series of contact elements on said switch, in circuit with the coil of said second relay, to determine the number of impulses of one nature that are sent over said line circuit.

21. In printing telegraph mechanism, a casing, a roller platen mounted on said casing and arranged to receive paper, type arranged in said casing to make impressions on said paper, a plurality of magnets for spacing and back spacing the impressions on said paper and for printing thereon, said magnets being arranged in groups in local circuits, slow and quick acting relays severally arranged to control said groups of magnets, a relay adapted to control said slow and quick acting relays, an arcuate switch actuated by the armature of said controlling relay and arranged to severally complete said local circuits and means for sending combinations of impulses of different natures through the coils of said controlling relay.

22. In a device of the class described, a type carriage, a series of parallel racks formed to engage said carriage, the teeth of one of said racks being intermediate with the teeth of another of said racks, resilient means for moving said carriage longitudinally on said racks, magnetic means for moving one of said racks longitudinally against the action of said resilient means for spacing, magnetic means for raising another of said racks for back spacing, and magnetic means for disengaging all of said racks from said carriage.

23. In printing telegraph mechanism a casing, a roller platen mounted on said casing and arranged to receive paper, type arranged in said casing to make impressions on said paper, a magnet for actuating said type, a series of racks extending substantially the length of said roller platen, mechanism for spacing impressions on said paper in engagement with said racks, a magnet for moving one of said racks longitudinally in one direction, spring actuated means for moving said spacing mechanism longitudinally in the opposite direction, a magnet for disengaging said racks from said spacing mechanism, relays arranged to control said magnets severally, the coils of said relays being included in the main line circuit, a plurality of manually operated keys mounted in said casing and means under control of said keys for sending combinations of impulses over the line circuit.

24. In a printing telegraph a casing, a roller platen mounted on said casing and arranged to receive paper, type arranged in

- 13 said casing to make impressions on said paper, magnets for actuating said type, a series of racks extending substantially the length of said roller platen and adapted to engage mechanism for spacing impressions on said paper, spacing mechanism in engagement with said racks, a magnet for moving one of said racks longitudinally in one direction, spring actuated means for moving 5 said spacing mechanism longitudinally in the opposite direction, a magnet for disengaging said racks from said spacing mechanism, a magnet adapted to move one of said racks upwardly, relays arranged to control said magnets severally, the coils of said relays being included in the main line circuit, a plurality of manually operated keys mounted in said casing and means under control of said keys for sending combinations of impulses over the line circuit.
- 14 10 20 25 30 35 40 45 50 55 60 65 70 75 80 85 90 95 100 105 110 115 120 125 130
- 13 25. In printing telegraph mechanism a casing, a roller platen mounted on said casing and arranged to receive paper, a type wheel and carriage therefor arranged in said casing to make impressions on said paper and to be moved longitudinally adjacent to said platen, a magnet for actuating said type wheel to make impressions, a series of racks extending substantially the length of said roller platen and adapted to engage said type wheel carriage, a magnet for moving one of said racks longitudinally in one direction, spring actuated means for moving said type carriage longitudinally in the opposite direction, a magnet for disengaging said racks from said type carriage, relays arranged to control said magnets severally, the coils of said relays being included in the main line circuit, a plurality of manually operated keys mounted in said casing and means under control of said keys for sending combinations of impulses over the line circuit.
- 13 25 30 35 40 45 50 55 60 65 70 75 80 85 90 95 100 105 110 115 120 125 130
- 13 26. In printing telegraph mechanism a casing, a roller platen mounted on said casing and arranged to receive paper, type arranged in said casing to make impressions on said paper, mechanism for spacing and back spacing the impressions on said paper, magnets for actuating said spacing and back spacing mechanism, a single pair of relays arranged to control said magnets, a plurality of levers arranged to be actuated by the armatures of said relays, type selecting mechanism actuated by said levers, a main line circuit including the coils of said relays and means for sending combinations of impulses over said line circuit.
- 13 26 30 35 40 45 50 55 60 65 70 75 80 85 90 95 100 105 110 115 120 125 130
- 13 27. In printing telegraph mechanism a casing, a roller platen mounted on said casing and arranged to receive paper, a type carriage mounted in said casing, type arranged on said carriage to make impressions on said paper, mechanism for spacing and back spacing said impressions, mechanism for shifting said type carriage, magnets for actuating said spacing, back spacing and shifting mechanism, a single pair of relays arranged to control said magnets, type selecting mechanism actuated by the armatures of said relays, a main line circuit including the coils of said relays and means for sending combinations of impulses over the main line circuit.
- 13 27 30 35 40 45 50 55 60 65 70 75 80 85 90 95 100 105 110 115 120 125 130
- 13 28. In printing telegraph mechanism a casing, a roller platen mounted on said casing and arranged to receive paper, type arranged in said casing to make impressions on said paper, a plurality of magnets for spacing and back spacing the impressions on said paper and for actuating said type to strike said paper, said magnets being arranged in groups in local circuits, slow and quick acting relays severally arranged to control said groups of magnets, a relay adapted to control said slow and quick acting relays, an arcuate switch actuated by the armature of said controlling relay and arranged to severally complete said local circuits, a line circuit including the coils of said controlling relay and means for sending combinations of impulses varying in length over said line circuit.
- 13 28 30 35 40 45 50 55 60 65 70 75 80 85 90 95 100 105 110 115 120 125 130
- 13 29. In printing telegraph mechanism a casing, a roller platen mounted on said casing and arranged to receive paper, a type wheel having upper and lower rows of type thereon arranged in said casing to make impressions on said paper with either row of type, a plurality of magnets for spacing and back spacing the impressions on said paper and magnets for actuating said type wheel to strike said paper and for shifting said wheel to strike said paper with the type of either row, said magnets being arranged in groups in local circuits, slow and quick acting relays severally arranged to control said groups of magnets, another relay adapted to control said slow and quick acting relays, a line circuit including the coils of said controlling relay and means for sending combinations of impulses varying in length over said main line circuit.
- 13 29 30 35 40 45 50 55 60 65 70 75 80 85 90 95 100 105 110 115 120 125 130
- 13 30. In printing telegraph mechanism a main line circuit, a plurality of manually operated typewriters provided with keys in local circuits, electrical printing mechanism arranged within each of said typewriters to be controlled by combinations of impulses of different natures passing over said main line circuit, means under control of said local circuits for sending combinations of impulses of different natures over said main line circuit, said means comprising a two part dial switch, one part of said dial switch being in said local circuits and the other part of said dial switch being in said main line circuit, means under control of said keys for rotating said dial switch, means mounted on said dial for lengthening impulses sent

over the line and a plurality of line relays in circuit with both parts of said dial switch.

31. A printing telegraph system comprising a two part selector dial, one part of said dial having upper and lower semi-circular conductor segments mounted thereon and a plurality of elements arranged to make contact with said segments, the other part of said dial having upper and lower intermeshing conductor segments and elements adapted to alternately make contact with said segments, a bar extending diametrically through the latter part of said dial and adapted to make contact with the contact elements on said part, a plurality of manually operated typewriters provided with keys in circuit with said dial, means under control of said keys severally for rotating said dial a predetermined degree, line relays in circuit with said dial, a single line circuit controlled by said relays and character selecting relays in said line circuit at both the sending and receiving stations.

32. In printing telegraph mechanism a casing, a roller platen mounted on said casing, a series of rods extending in parallel relation with said roller platen within said casing, a type carriage slidable longitudinally on said rods, a type wheel mounted on said carriage and arranged to strike said roller platen, spring actuated means for moving said carriage longitudinally in one direction, means for holding said carriage in predetermined positions, a magnet arranged to move said carriage step by step in the opposite direction, a second magnet to cause said type wheel to strike said roller platen, a third magnet to release said carriage, gearing to rotate said type wheel simultaneously with the stroke thereof, a bar arranged on said carriage to stop rotation of said type wheel in predetermined positions, local circuits including the coils of said magnets, relays arranged to control said local circuits, the armatures of said relays being adapted to actuate said bar, a main line circuit including the coils of said relays and means for sending combinations of electrical impulses over said main line circuit comprising line relays, a selector dial and a plurality of keys arranged in local circuits to control said dial and line relays.

33. In printing telegraph mechanism a casing, a roller platen mounted on said casing, a series of rods extending parallel to said roller platen within said casing, a type carriage slidable longitudinally on said rods, a type wheel mounted on said carriage and arranged to strike said roller platen,

spring actuated means for moving said carriage longitudinally to the left, a series of racks for holding said carriage in predetermined positions, a magnet arranged to move said carriage step by step to the right, a second magnet to cause said type wheel to strike said roller platen, a third magnet to release said carriage, a fourth magnet adapted to actuate said racks to move said carriage step by step to the left, gearing to rotate said type wheel simultaneously with the stroke thereof, a bar arranged on said carriage to stop rotation of said type wheel in predetermined positions, local circuits including the coils of said magnets, relays arranged to control said local circuits, the armatures of said relays being adapted to actuate said bar, a main line circuit including the coils of said relays and means for sending combinations of electrical impulses over said main line circuit comprising line relays, a selector dial and a plurality of keys arranged in local circuits to control said dial and line relays.

34. In printing telegraph mechanism a casing, a roller platen mounted on said casing, a series of rods extending in parallel relation with said roller platen within said casing, a type carriage slidable longitudinally on said rods, a type wheel mounted on said carriage and arranged to strike said roller platen, spring actuated means for moving said carriage longitudinally in one direction, means for holding said carriage in predetermined positions, a magnet arranged to move said carriage step by step in the opposite direction, a second magnet to cause said type wheel to strike said roller platen, a third magnet to release said carriage, gearing to rotate said type wheel simultaneously with the stroke thereof, a bar arranged on said carriage to stop rotation of said type wheel in predetermined positions, levers linked together and adapted to severally actuate said bar through different arcs, local circuits including the coils of said magnets, relays arranged to control said local circuits, the armatures of said relays being adapted to actuate said levers, a main line circuit including the coils of said relays and means for sending combinations of electrical impulses over said main line circuit comprising line relays, a selector dial and a plurality of keys arranged in local circuits to control said dial and line relays.

In testimony whereof, I have hereunto signed my name to this specification.

EINAR G. C. LOFGREN.
